UNITED STATES PATENT OFFICE.

FLETCHER M. HAWKINS, OF CASH, TEXAS.

CULTIVATOR ATTACHMENT.

Application filed November 17, 1924. Serial No. 750,347.

To all whom it may concern:

Be it known that I, FLETCHER M. HAWKINS, a citizen of the United States, residing at Cash, in the county of Hunt and 5 State of Texas, have invented a new and useful Cultivator Attachment, of which the following is a specification.

This invention relates to an attachment for cultivators and more particularly to 10 means for connecting the shanks of cultivator blades or other ground engaging elements to the beams of cultivators.

One of the objects of the invention is to provide a simple form of attachment which 15 can be applied readily to a beam and which, when so applied, can be used for holding the shank of the engaged element at any angle, the shank being shiftable by the use of a universal connection with the beam engag- 20 ing portion of the structure.

With the foregoing and other objects in view which will appear as the description proceeds, the invention resides in the combination and arrangement of parts and in 25 the details of construction hereinafter described and claimed, it being understood that changes in the precise embodiment of the invention herein disclosed may be made within the scope of what is claimed with- 30 out departing from the spirit of the invention.

In the accompanying drawings the preferred form of the invention has been shown.

35 In said drawings:

Figure 1 is a perspective view of a portion of a cultivator having the present improvements combined therewith.

Fig. 2 is a plan view of one of the attaching elements.

Fig. 3 is a central longitudinal section therethrough on line 3—3, Fig. 2.

Fig. 4 is a section on line 4—4, Fig. 2.

Fig. 5 is an elevation of a removable member of the attachment shown in Figs. 2 and 3.

Fig. 6 is a plan view of another form of element.

Fig. 7 is a rear elevation thereof, the beam on which it is mounted being shown in section.

Fig. 8 is a plan view of another form of the device.

Fig. 9 is a rear elevation thereof showing the beam in section.

Referring to the figures by characters of reference A designates a cultivator structure provided with beams B formed of metal and which, in the present instance, are made up of spaced metal strips providing a structure which is stepped from end to end. In the form illustrated, it is desired to support the ground engaging element at the different steps of each beam so that the elements on each beam will not travel in the same path. For the purpose of connecting a ground engaging element to the front portion of the beam where the metal strips are the farthest apart, a device such as shown in detail in Figs. 2, 3 60 and 4 is preferably used. This includes a block 1 having a recess 2 in one end for the reception of one of the strips b of the beam B, the said strip being held to the block by a bolt 3 extending therethrough 65 and into the end of the block as shown in Fig. 3. The other strip of the beam, indicated at b' is extended through the block and held against one end thereof by a bolt 4 which is extended downwardly through 70 the block and contacts with one side of the strip b'. A head 5 is extended from this last mentioned end block 1 and has a rounded socket 6 intersecting a channel 7, which extends across the head from the top 75 to the bottom thereof. Spaced recesses 8 are formed in the end of the block 1 adjacent head 5 and are designed to receive 80 tongues 9 extending from a clamping block 10 which is provided in one face with a 85 rounded recess 11. This recess intersects a channel 12 which extends across the block from the top to the bottom thereof. A ball 13 is adapted to be seated between the head 90 and the block 10 and a bolt 14 is insertable transversely through the head 5 and block 10 and, when tightened, will hold the tongues 9 in the recesses 8 and bind upon the ball 13 so as to hold it against rotation. 95

The shank S of a ground engaging element G which can be in the form of a cultivator blade is adapted to be fitted snugly within the ball and may be adjusted longitudinally therein and held in any suitable manner not shown. This block is adapted 100 to extend through the opposed channels 7 and 12 and obviously by loosening bolt 14, the ball 13 can be adjusted angularly in any direction so as to vary the angle of the shank 7.

Where the attachment is to be applied to a single strip of the beam B as shown in Figs. 6 and 7 the structure can be modified by providing a solid block 15 having a transverse opening 16 for the reception of the beam strip b'. A set screw 17 may be mounted in the block for engaging the strip b' to hold the block against movement thereon. The block is cut away at one side to provide a recess 18 and another block 19 is adapted to be removably mounted on this recess. This block 19 is constructed in the same manner as the block shown in Fig. 5, the tongues 20 thereon being adapted to fit within recesses 21 in the block 15. Opposed rounded recesses 22 are formed in the two blocks to receive a ball 23 through which the shank S extends. A bolt 24 is extended transversely through the blocks and by tightening the same, said blocks can be nested securely upon the ball and to hold it against rotation.

Instead of utilizing a set screw for holding the attachment to the beam, one end of the block can be provided with a transverse opening 25 to receive the beam as shown in Figs. 8 and 9. This end of the block can be split as at 26 and a bolt 27 can be extended through the split portion so that by tightening the bolt, said split portion can be contracted to bind upon that portion of the beam engaged by the attachment. In either respect this modified construction is similar to that illustrated in Fig. 6 except, if preferred, those ends of the blocks remote from the beam can be reduced in thickness to provide flanges 28 for receiving the clamping bolt 29.

It has been found in practice that by providing a structure such as described, ground engaging elements can be securely held to the cultivator beam at any angle to which they may be adjusted. The attachments are simple, durable and efficient, and can be produced at low cost, and can be easily applied and removed without requiring the services of a skilled mechanic.

What is claimed is:—

1. An attachment of the class described including a block having a transverse space therein for the reception of a beam, means engaging the block for binding the same upon the beam, a clamping block fitted within the first named block, cooperating means upon the blocks for holding them assembled at one end, said blocks having opposed recesses in the meeting faces thereof, a shank engaging the ball seated within the recesses, and means for drawing the blocks together at one end to bind them upon the ball. 50 55

2. An attachment of the class described including a block having a beam receiving space extending transversely thereof, means engaging the block for binding it upon the beam, said block having a cut away portion 60 or recess therein, a clamping block removably mounted in the recess, a tongue extending from the clamping block and projecting detachably into the first named block, a ball interposed between and projecting into the 70 blocks, and means for drawing the blocks together to bind upon the ball, said ball constituting shank holding means. 75

3. An attachment for a cultivator or the like including a block having a transverse beam receiving space, means engaging the block for binding it upon a beam within said space, said block having a cut away portion forming a recess, a clamping block removably seated in the recess, a tongue projecting 80 from one end thereof and into the first named block to hold the blocks assembled at one end, a ball interposed between and projecting into the blocks, said ball being adjustable angularly in any direction about 85 its center, there being a diametrical shank receiving opening in the ball, and means engaging the blocks for binding them upon the ball. 90

In testimony that I claim the foregoing as my own, I have hereto affixed my signature in the presence of two witnesses.

FLETCHER M. HAWKINS.
